(57) **CLAIM**

The ornamental design for a workstation, as shown and described.

DESCRIPTION

FIG. 1 is a perspective view of a workstation showing our new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a rear elevation view thereof; and,

FIG. 8 is an exploded perspective view of the workstation, showing the mobile cart pulled away from the slat wall docking station.

The broken lines shown in the drawings depict portions of the article and form no part of the claimed design.

1 Claim, 6 Drawing Sheets
